UNITED STATES PATENT OFFICE

2,692,788

VEHICLE DOOR LOCK

Elijah J. Willis, Morehead City, N. C., assignor of
one-half to Daniel G. Bell, Morehead City, N. C.

Application May 20, 1953, Serial No. 356,218

2 Claims. (Cl. 292—267)

1

This invention relates to a door lock, and more particularly to a door lock for a vehicle such as an automobile.

The object of the invention is to provide a door lock which will maintain a door securely fastened so that the door will not accidentally open.

Another object of the invention is to provide a vehicle door lock which is constructed so that accidental opening of the door will be prevented whereby occupants of the vehicle will not accidentally fall out of the vehicle, the door lock of the present invention being readily installed in new or used vehicles.

A further object of the invention is to provide a vehicle door lock which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a side elevational view showing a portion of a vehicle in broken lines, with the door lock of the present invention mounted therein.

Figure 2 is an enlarged fragmentary elevational view showing the pawls or dogs moved away from the teeth to permit opening of the door.

Figure 3 is a sectional view taken on the line 3—3 of Figure 2.

Figure 4 is a sectional view taken on the line 4—4 of Figure 5.

Figure 5 is an enlarged side elevational view of the door lock showing the position of the parts when the lock is being used for preventing accidental opening of the door.

Referring in detail to the drawings, the numeral 10 designates a portion of the vehicle body or frame, Figure 1, while the numeral 11 designates a portion of a door which may be the door of an automobile. The door 11 may be hingedly connected to the frame 10 by suitable hinges 12.

Positioned within a portion of the frame 10 is a plate 14, the plate 14 being secured to the frame 10 by suitable securing elements such as screws 15. Mounted within the movable door 11 is a casing or housing 16 which includes a pair of sections 17 and 18 that are detachably connected together by means of bolts 19, Figure 4. Slidably mounted in the hollow casing 16 is a tongue 20 which is provided with a plurality of teeth 21 on each longitudinal edge thereof. A

2

plate 9 may be detachably connected to the housing, and this plate can be removed in order to gain access to the interior of the housing.

A pair of pawls or dogs 22 and 24 are mounted for movement into and out of locking engagement with the teeth 21. The pawl 22 is pivotally mounted in the housing 16 by means of a pin 23, and the other pawl 24 is pivotally mounted in the housing 16 by means of a pin 25. A coil spring 26 interconnects the pair of pawls 22 and 24 together so as to normally urge the free ends of the pawls into locking engagement with the teeth 21.

A lever 27 has one end pivotally connected to the pawl 24 by means of a pin 28, and a link 29 has one end pivotally connected to the other pawl 22 by means of a pin 30. The link 29 is also pivotally connected to the lever 27 by means of a pin 31, Figure 5.

The numeral 32 designates a conventional knob or grip which can be manually gripped in order to open or close the door after the lock has been adjusted. A pin 34 pivotally connects an end of an arm 33 to the lever 27, and a finger 35 is pivotally connected to the other end of the arm 33 by means of a pin 36, there being a handle 37 which is adapted to be moved in a counter-clockwise direction, Figure 1, when the door is to be opened. A hinge 38 serves to hingedly connect the tongue 20 to the plate 14.

From the foregoing it is apparent that a lock has been provided which is especially suitable for vehicle doors such as automobile doors. In Figure 5 the parts are shown in locked position so that the free ends of the pawls 22 and 24 engage the teeth 21 to prevent sliding movement of the tongue 20 in the casing 16 so that opening or swinging movement of the door 11 is prevented. In order to open the door 11, it is only necessary to lift the handle 37 whereby the arm 33 causes the lever 27 and link 29 to move the pawls 22 and 24 apart against the tension of the coil spring 26. Thus, the door 11 will be free to swing open since the pawls will not engage the teeth 21. After the door has been closed the spring 26 will urge the free ends of the pawls 22 and 24 into engagement with the teeth 21 so that accidental opening of the door is prevented.

I claim:

1. In combination, a door frame, a plate positioned in said door frame and secured thereto, a door hingedly connected to said frame, a hollow housing positioned in said door and including a pair of sections detachably connected together, a tongue slidably mounted in said hous-

ing and provided with a plurality of teeth extending along each longitudinal edge, said tongue being hingedly connected to said plate, a pair of pawls pivotally mounted in said housing and mounted for movement into and out of engagement with said teeth, a lever having one end pivotally connected to one of said pawls, a link having one end pivotally connected to said lever and its other end pivotally connected to the other of said pawls, an arm having one end pivotally connected to said lever, and a door handle connected to said arm.

2. The apparatus as described in claim 1, and further including a coil spring interconnecting

said pair of pawls for maintaining said pawls in engagement with said teeth.
